UNITED STATES PATENT OFFICE.

ALFRED HOUÉE, OF RENNES, FRANCE.

ROLLING SKATE.

SPECIFICATION forming part of Letters Patent No. 623,717, dated April 25, 1899.

Application filed September 16, 1898. Serial No. 691,104. (No model.)

To all whom it may concern:

Be it known that I, ALFRED HOUÉE, a citizen of the French Republic, residing at Rennes, France, have invented certain new and useful Improvements in Rolling Skates; and I do hereby declare the following to be a full, clear, and exact description of the invention, such as will enable others skilled in the art to which it appertains to make and use the same.

10 My invention relates to means of human locomotion; and the object of the invention is to provide a wheel device adapted to be attached to the legs and feet of the user and which permits of a rapid locomotion with 15 neither strain nor danger.

The essential feature of my invention is a cycle-wheel, the axis of which is attached to the leg by means of a support pivoted on this axis and located at the side of the wheel. 20 The lower end of this support carries a movable skate on which the foot rests and at the rear extension of which a small supporting-wheel is provided for the purpose of maintaining the equilibrium of an inexperienced user or to permit the latter to take a rest; but 25 normally when the device is in motion this supporting-wheel rarely comes in contact with the ground.

In the accompanying drawings, Figure 1 is 30 a side view of the device; and Fig. 2, a front view thereof, the cycle-wheel appearing in section.

A is the cycle or driving wheel, rotating on the axle B, rigidly secured in a support or 35 standard C to be attached to the leg. At the lower end of this standard is an axle D, carrying a skate E, pivoted thereon.

The skate is attached to the foot in the usual manner or by any suitable means, but 40 in such wise as to leave the foot quite free for all movements and independent of the movements of the leg.

At the rear of the skate is mounted an ad-

ditional wheel F, and in front is mounted a roller G, that normally remains in its elevated 45 position and only has rolling contact with the ground when any accidental shock occurs in the course of running. The wheel F, as above mentioned, serves merely as a support when the device is stationary.

The axle B carries a ratchet-wheel H, that is rigidly secured to the drive-wheel A and in which engages a pawl J, pivoted on a stud K, fixed in the leg-support C.

The main feature of the invention is the 55 arrangement of the wheels, which when in use are located one on either side of the skater and which are actuated not only by the feet, but also and chiefly by the legs. The feet being thus located below the axis of the large wheel, the latter may be of any appropriate size and shall always be closely attached to the leg, which, with the foot, will bear all the strain.

Having thus described my invention, I claim—

The combination of the leg-support C, provided with suitable fastening means, an axle B rigid thereon, a drive-wheel A rotatably mounted on said axle, a ratchet-wheel H fixed to its hub, a pawl J pivoted to stud K on said support and adapted to engage with said ratchet-wheel, a skate E pivoted at D to the base of said leg-support, a roller G carried in an extended portion of the forward end of said skate, with its lower periphery substantially 75 in the same plane as the skate, and a wheel F rotatable in the rear extremity of the skate and adapted to steady the device, substantially as specified.

In testimony whereof I affix my signature 80 in presence of two witnesses.

ALFRED HOUÉE.
